IVAR W. BROGGER, OF SPRINGFIELD, NEW JERSEY, ASSIGNOR TO TIFFANY MANUFACTURING COMPANY, OF NEWARK, NEW JERSEY

AMMETER

Application filed November 18, 1929. Serial No. 407,903.

This invention relates to improvements in electrical measuring instruments for measuring the flow of current.

One of the objects of my invention is to provide an ammeter composed of a minimum number of parts whereby the cost of manufacture may be greatly reduced.

Another object of my invention is to provide a unitary construction in which all of the working parts are mounted on a single insulator.

My invention will be readily understood with reference to the annexed drawings, wherein:

15 Figure 1 is a plan view of the unitary structure carrying the working parts of the instrument, without the casing or the scale, and with one of the contact studs removed.

20 Figure 2 is a side elevation of Figure 1, but with the scale plate in position.

Figure 3 is a view of the back side of Figure 1, the scale plate being shown in dotted line.

25 Figure 4 is a side elevation of a flux-distributing member, or field spreader used in association with the magnet and armature.

Figure 5 is a plan view of an insulator used to cover the magnet.

30 Figure 6 is a rear view of the dial plate.

In the different views, 1 is an insulator of strong material and preferably one which is not susceptible to changes in humidity or temperature. The insulator 1 is provided with a slot 2 within which is pressed a permanent magnet 3. Lying flat on the dial side of the insulator 1 and directly over the magnet 3, is a plate 4, preferably of non-magnetic material such as brass. Passing through opposite ends of the metallic plate 4, are a pair 35 of studs 5, the right-hand one in Figure 1 being removed to show a square hole 6 which is punched in the plate 4 to receive the square part of the stud 5 to prevent the same from turning when the clamping nuts 7 are drawn up. Preferably a thin insulator 8, shown in plan view in Figure 5, is placed directly 40 against the back of the insulator 1 to cover the magnet 3 on the back side and also to hold it in position within the slot 2.

45 The plate 4 is provided with an arm 9 which extends from the body part of the plate upwardly and inwardly over the plate. Between the arm 9 and the body portion of the plate 4, there is pivoted an armature 10 constructed in the manner shown in Mason Patent 1,680,465, issued on August 14, 1928. To this armature is fastened a pointer 11. The insulator 1 is provided with a pair of oppositely disposed notches 12 to receive fingers 13 which extend from the flanges 14 formed on the side of the dial plate 15, which is also provided with a notch 16 to clear the armature 10 and the arm 9 as is clearly indicated in Figures 2 and 3.

50 In order to get a scale which is fairly uniform, I have found it necessary to use a device which acts as a spreader of the magnetic flux, and this field spreader preferably takes the form of a soft iron strip 17 which is positioned in a transverse direction across the magnet 3 and between it and the plate 4. The member 17 is thereby held in position by the plate 4 when the same is clamped in position on the insulator 1.

55 It will be understood that when current passes from one stud to the other through the plate 4, a magnetic field is set up which in conjunction with the magnet 3, acts on the armature 10 to turn the same and to give the indications on the scale 15. I have found that without the flux spreader above described, the scale divisions at the center, such as indicated in Figure 3, will be wider than at the ends, but by using this device, I can obtain a substantially uniform scale, only part of 60 which is shown.

65 The flux spreader 17 is preferably longer than the armature 10 and has an upturned end as shown in Figure 4, that engages the arm 9 which then acts as a stop for the member 17, whereby it can only be pushed inwardly to the point where the end 18 projects a short distance beyond the inner edge of the magnet 3.

Having thus described my invention, what I claim is:

70 1. An ammeter including an insulator having a slot therein, a magnet positioned in said slot, a metallic plate overlying the magnet on one side of the insulator and held thereto 75

by circuit connecting studs passing through the plate at opposite ends thereof, adjacent the ends of the magnet, an arm on the plate extending upwardly and inwardly thereover, 5 an armature of magnetic material pivoted between said arm and the body part of said plate, a pointer carried by the armature, and a scale plate carried by the insulator.

2. An ammeter having its working parts 10 carried on a single insulator, said working parts comprising; a magnet set into the insulator, a metallic plate extending over the magnet on one side of the insulator, contact studs extending through opposite ends 15 of the plate and the insulator and clamped thereto, an armature pivotally mounted on the plate, and a pointer moved by the armature.

3. An ammeter having its working parts 20 carried on a single insulator, said working parts comprising; a magnet set into the insulator, a metallic plate extending over the magnet on one side of the insulator, contact studs extending through opposite ends of the 25 plate and the insulator and clamped thereto, an armature pivotally mounted on the plate, a pointer moved by the armature, and a soft iron strip extending across the magnet and armature, but between the magnet and the 30 plate and at right angles to the magnet.

4. An ammeter having its working parts carried on a single insulator, said working parts comprising; a magnet set into the insulator, a metallic plate extending over the magnet 35 on one side of the insulator, contact studs extending through opposite ends of the plate and the insulator and clamped thereto, an armature pivotally mounted on the plate, a pointer carried by the armature, and a flux- 40 distributor comprising a strip of magnetic material held against the central part of the magnet by said plate, the strip being positioned transversely of the magnet and extending beyond the magnet at one side thereof.

45 5. An ammeter having its working parts carried on a single insulator, said working parts comprising; a magnet set into the insulator and of substantially the same thickness as the insulator, a metallic plate lying flat 50 on one side of the insulator and extending over the magnet, contact studs extending through opposite ends of the plate and through the insulator and clamped thereto, an arm integral with said plate, an armature 55 pivoted between the arm and the body part of the plate, a pointer carried by the armature, and a flux-distributing member comprising; a strip of magnetic material extending at right 60 angles to the magnet between the plate and magnet and beyond the magnet on one side thereof, said distributing member having an upturned end to engage said plate arm to limit the position of said member.

65 In testimony whereof, I affix my signature.
IVAR W. BROGGER.
